UNITED STATES PATENT OFFICE.

GEORGE EDGAR DEAN, OF SCRANTON, PENNSYLVANIA.

POCKET-CASE.

1,010,872.

Specification of Letters Patent.

Patented Dec. 5, 1911.

Application filed September 29, 1910. Serial No. 584,524.

To all whom it may concern:

Be it known that I, GEORGE EDGAR DEAN, a citizen of the United States, residing at Scranton, in the county of Lackawanna and 5 State of Pennsylvania, have invented new and useful Improvements in Pocket-Cases, of which the following is a specification.

The present invention has reference to improvements in pocket cases adapted to 10 contain pens, pencils and various other articles, and to protect and retain the same.

It comprehends primarily the production of a case of the general class specified, which, when in place in the pocket of a vest or 15 other garment, will be completely invisible, and will, at the same time, be held against accidental displacement, the latter object being attained through the medium of clips that are likewise wholly concealed within 20 the pocket, thereby avoiding the unsightly appearance presented by the visible retaining devices ordinarily employed, in connection with the cases now in use.

A structural embodiment of the invention 25 is illustrated in the accompanying drawing, wherein—

Figures 1 and 2 are perspective views of the device taken from opposite sides. Figs. 3 and 4 are vertical sectional views taken 30 at right angles to each other on the lines 3—3 and 4—4 of Fig. 5. Fig. 5 is a plan view. Fig. 6 is a front elevation, illustrating the case in position in a pocket.

The case shown in said drawing is constructed from a blank of suitable sheet material, preferably thin metal or celluloid, the blank being stamped from the sheet by a die of the proper configuration and subsequently joined at its edges in any desired manner.

40 The particular process or method of construction forms, however, no part of the present invention but will be made the subject of a separate application to be filed hereafter. It is sufficient, therefore, to state 45 that the component parts of the case are of integral construction, and are integrally connected together. The said parts comprise a front piece 7 which extends uninterruptedly across the entire case, a pair of tubular

50 pockets or receptacles 8 forming continuations of the ends of said front piece, and a back piece 9 arranged between said tubular portions 8 and connecting the same. The front piece has a very slight transverse curvature at its edges, and is otherwise substantially flat, so as to fit in the pocket without

occasioning an unsightly bulge therein. The back piece, on the other hand, has an appreciable bowing, as shown, so as to cooperate with the front piece in producing the 60 central pocket or receptacle 10. This receptacle may or may not be lined, according to the character of the article or articles it is designed to contain. The two tubular receptacles 8 are preferably designed to receive pens, pencils and similar articles, this being dependent to some extent upon the diameters of said receptacles, while the central receptacle 10 is shown, in the construction illustrated, as constituting a holder for 70 spectacles or eye glasses, a portion of the upper part of the front piece being cut away, as indicated by the numeral 11, to permit the glasses or other article to be readily removed. While an article of the character just specified is primarily intended to be carried in said receptacle 10, it is to be understood that no limitation to this particular article is contemplated, since the receptacle may obviously contain articles of 80 an entirely different type.

In order to retain the articles in the two end receptacles the rear portions of the walls of the latter are slit longitudinally to produce spring tongues 12, the lower portions of which are bent inward so as to project into the interior of said receptacles and bear against the articles therein. Spring tongues are also employed to effect the retention of the case in a garment pocket. 90 These springs, which are indicated by the numeral 13, are preferably constructed separately from the case and are arranged against the outer side portions of the walls of the end receptacles, to which portions 95 they are suitably attached at their lower ends. Toward their upper ends, said springs are bent to produce outwardly projecting angular shoulders 14, the horizontal upper arms 15 of which are arranged for movement through perforations 16 formed in the walls of the end receptacles 8. Above said shoulders, the springs are formed with straight portions 17 terminating in enlarged heads 18 that project above and normally 100 overhang the upper edges of the walls of said end receptacles. The vertical portions 17 just mentioned are disposed against the inner faces of said walls by the tension of the springs.

In order to permit the case to be completely invisible when in use, it is made of

the same or slightly less height than a vest pocket of ordinary depth. When in place therein, the shoulders 14 formed on the spring tongues 13 will move outward and 5 will project beneath the so-called "welt" of the pocket, as shown in Fig. 6, thus preventing accidental displacement of the case therefrom. It will be seen, therefore, that until the heads of the springs are pressed 10 inward, the shoulders will remain in the position specified, and will, in consequence, preclude withdrawal of the case. The springs 12 serve to retain the articles in the end receptacles and also to prevent said 15 articles from rattling. The bottoms of these receptacles are closed and are intended to be fluid-tight, to prevent soiling of the garment by any ink which may escape from a leaky fountain pen. The case bottom is 20 preferably rounded, so as to prevent rapid wear upon the lining of the garment pocket.

I claim as my invention:

1. A pocket case having one of its side edges formed with an opening, and a retaining spring secured to said edge and formed with an outwardly-projecting shoulder, one arm of which extends inwardly through said opening.

2. A pocket case comprising a series of mutually-connected vertical receptacles arranged side by side, the end receptacles being provided with exteriorly-located retaining springs, each of which is provided intermediate its ends with an outwardly-projecting angular shoulder arranged to lie normally beneath the welt of the pocket, and is provided at its upper end with a head for forcing said shoulder out of such position, the movements of said springs in both directions being relative to the corresponding 40 receptacles.

3. A substantially rigid pocket case formed with an opening, and a retaining spring secured to said case and provided with an outwardly-projecting shoulder, having a portion thereof extending inwardly through said opening and terminating in an operating head.

In testimony whereof I have hereunto set my hand in presence of two subscribing witnesses.

GEORGE EDGAR DEAN.
